R. W. DONNELL

WIRE STRETCHER EXTENSION

Filed Dec. 31, 1923

INVENTOR.
R. W. Donnell,

BY
Geo. P. Kimmel.
ATTORNEY.

UNITED STATES PATENT OFFICE.

RALPH W. DONNELL, OF NEVADA, MISSOURI.

WIRE-STRETCHER EXTENSION.

Application filed December 31, 1923. Serial No. 683,690.

To all whom it may concern:

Be it known that I, RALPH W. DONNELL, a citizen of the United States, residing at Nevada, in the county of Vernon and State 5 of Missouri, have invented certain new and useful Improvements in Wire-Stretcher Extensions, of which the following is a specification.

This invention relates to extension devices 10 for use with wire stretchers, and relates particularly to a device which may be used with any type of stretcher.

The primary object of this invention is the provision in a manner as hereinafter 15 set forth, of an extension means for use with wire stretchers, whereby the stretching device may be supported beyond the last post in the fence line in such a manner as to permit the proper stretching of the wire between the last two posts.

Another object of the invention is the provision in a manner as hereinafter set forth, of an extension device for wire stretchers which may be adjusted to any 25 height of post, and which when in adjusted position will be more tightly held against the post, as the tension is increased upon the wire being stretched by the stretcher.

A further and final object of the invention, 30 is the provision in a manner as hereinafter set forth, of an extension device for wire stretchers which may be folded when not in use, which is light, strong and durable, and inexpensive to manufacture.

The invention will be best understood from a consideration of the following detailed description taken in connection with the accompanying drawings forming part of this specification, with the understanding 35 that the invention is not confined to any strict conformity with the showing of the drawings, but may be changed and modified so long as such changes and modifications mark no material departure from the salient 40 features of the invention.

In the drawings:—

Figure 1 is an elevation of the device embodying this invention as it would appear when in use.

Fig. 2 is a top plan view of the same, and,

Fig. 3 is a detail showing the connection between the legs of the device and the hook upon which the wire stretcher may be engaged.

Referring now to the drawings in detail, wherein like numerals of reference indicate

corresponding parts throughout the several views of the drawings, the device embodying this invention is shown as comprising a pair of leg members 1 and 2, each having 60 one of its ends sharpened as at 3, and having their other ends crossed as at 4.

Passed through the crossed ends 4 of the legs 1 and 2, is a combined hook and eye member 5, having the hook 6 and the eye 7 65 separated by a shank 8, which shank extends through the cross members 1 and 2 to secure them together. The crossed ends of the legs 1 and 2 are pivoted on the shank 8 of this combined member 5.

Engaged in the eye 7 of the member 5 is a coupling chain 9 carrying at its other end a hook 10. The purpose of this chain and hook is as follows. When the leg members 1 and 2 are opened out and their points 70 3 made to engage a post 11 as indicated in Fig. 1, the chain 9 is extended rearwardly to the post and extended partially around the post, and the hook 10 is engaged in the post upon the side opposite from the side approached by the chain, as is clearly shown in Fig. 2. The chain is normally of a greater length than either of the leg members 1 and 2, so that when the leg members 75

are in position, the free end of the chain which carries the hook, can be passed around the post and the hook engaged in the opposite side of the post. After the device has been set up in this position, a wire stretcher 12 of any approved design is engaged with the hook 6, and upon putting tension upon the wire 13, attached to the stretcher 12, the outer or crossed ends 4 of the member will be drawn over toward the side upon which the stretcher is located, 80 thus putting tension upon the chain 9 and hook 10 and also upon the legs 1 and 2 to securely and rigidly hold the device in position.

One of the leg members has its pointed 85 end offset, as at 14, to obviate the possibility of splitting a light post, were the extension device applied to a light post.

Having thus described the invention, what I claim is:—

1. A combined wire stretcher extension brace and suspension device, formed of a pair of rigid leg members each having one end sharpened for engagement with a fence post, a combined hook and eye member including a shank connecting the hook with the eye, the said shank extending through

and pivotally connecting one end of said members together, a flexible coupling element connected at one end to said eye, and adapted to engage the fence post for securing the said device in a lateral position with respect to the post, and said hook adapted to be connected to a wire stretcher upon the side of the leg members opposite to that occupied by said flexible coupling element.

2. A combined wire stretcher extension brace and suspension device, formed of a pair of rigid leg members each having one end sharpened for engagement with a fence post, and one of said leg members further being offset at its pointed end, a combined

hook and eye member including a shank connecting the hook with the eye, said shank extending through and pivotally connecting one end of said members together, a flexible coupling element connected at one end to said eye, a hook at the other end of said flexible element adapted to engage in the fence post for securing the said device in a lateral position with respect to the post, and said shank carried hook adapted to be connected to a wire stretcher at the side of said leg members opposite to the side from which said flexible element extends.

In testimony whereof, I affix my signature hereto.

RALPH W. DONNELL.
